UNITED STATES PATENT OFFICE.

ROBERT W. MILLER, OF WATERLOO, IOWA.

MEASURING HOPPER.

Application filed August 3, 1927. Serial No. 210,432.

My invention relates to improvements in measuring hoppers, and the object of my improvement is to supply a hopper with removable adjustable division means to permit different materials to be deposited in segregated measured quantities in the hopper to be removed or delivered thence in any manner desired.

This object I have accomplished by the means which are hereinafter described and claimed, and which are illustrated in the accompanying drawings, in which, Fig. 1 is a perspective view of a tiltable hopper supplied with my improved means for subdividing its interior space into adjustably varied compartments, and Fig. 2 is a detail perspective view of one of the division contrivances thereof as detached from the hopper.

My invention is not restricted to the precise construction and arrangement of parts herein shown and described, nor to the various details thereof, as the same may be modified or rearranged in various particulars without departing from the spirit and scope of my invention, one practical embodiment of which has been illustrated and described without attempting to show all of the various forms and modifications in which my invention might be embodied.

The open top hopper of my invention is of rectangular shape and has a discharge lip or funnel 3 along one side which opens into the interior of the hopper 1 along the entire length of the latter, but an imperforate gate 35 or plate 8 serves as a removable gate or closure for said communication, being scrolled at the top around a longitudinally inclosed rod 9 whose ends project oppositely therefrom to serve as handles extending beyond the sides of the hopper. This plate or gate body 9 is positioned to the rear of the rear portion of a flange 2 which extends all around the upper edge of the hopper as a flat margin, and the front and rear parts of the flange having therealong respectively an aligned row of spaced holes 10, preferably indicating graduated spaces of the interior of the hopper for adjusting a division contrivance therein.

The plate 9 therefore is seated to slide up or down in end grooves or slideways furnished by the said rear flange 2 and the converging parts of the side walls of the delivery funnel 3.

The hopper 1 may be otherwise shaped, and have an outlet otherwise arranged, and the

hopper may be fixed or tiltable or otherwise movable without deviating from my invention. Being shown tiltable, and shaped for particularly serving as a measuring hopper for a concrete mixing machine, it has been shown with pintles 4 on opposite sides, upon which may be pivotally mounted arms 5 having terminal furcations 6 between which may be mounted rotatable rollers 7 to travel up an inclined surface previously to dumping the contents of the hopper by way of its mouth or funnel outlet 3 upon tilting over the hopper by any appropriate means.

The front longitudinal wall of the hopper 70 has been shown lower in height than the space under the rear longitudinal flange 2, but the dimensions may be otherwise.

My device may, within scope of its allowable modifications, be used for adjustably measuring different ingredients of any desired mixture for a compound. As shown, it is exemplified for use in measuring the ingredients of concrete or the like, such as cement, sand and broken stone. Any desired type of division contrivance may be assembled with the hopper and its apertured front and rear flanges 2, such as a plate having end connecting devices for said apertured flanges. I have shown substantially this means, but in 80 the form of a U-shaped plate 11, whose opposite upright walls serve as the division contrivance to segregate at each side thereof spaces or compartments to receive stated quantities of different materials, such as sand and broken stone, the inner space of the U-shaped device 11 being utilized preferably to receive a measured charge of powdered cement.

The U-shaped device 11 has outwardly directed flat horizontal side flanges 12 apertured near their ends to be placed in registration with any of the holes 10 of the front and rear end flanges 2 respectively. The rear end parts of the device 11 at the top may be provided with elongated open notches 15 to seat the rear part of the device upon the rear flange 2, and hold the device in place while in use, removably. Headed or eyed pins 13 are used to insert into the registering holes 14 of the device and the holes 10 of the hopper flanges to secure the device 11 in adjusted position.

This division contrivance will function successfully in the measuring of a number of different materials differing in unitary proportions, but I have added an element or de-

vice suitable for subdividing the interior of the U-shaped device fractionally, so that a one-half proportion or other fractional proportion of cement may be easily and quickly measured for addition to the other ingredients of the desired compound.

This in its simplest form, is a rectangular plate 16 having corner apertured lugs 19-20 at the front end of the plate. The plate may 10 be positioned within the device 11 sloping rearwardly and downwardly at a desired angle according to its adjustment. The opposite side walls of the device 11 have a plurality of transversely alined holes 17 at graduated spaces as determined in advance for different proportions of the material, and a headed or eyed pin 18 is inserted through the holes 17 and the holes 20 of the lugs 19 when in registration as adjusted. The material 20 is then deposited upon the plate 16, the measure whereof is determined by the particular adjustment.

It will be observed, that when the different compartments of the hopper as adjusted have 25 been filled with the measured quantities of the different ingredients, that the whole may be discharged upon tilting the hopper, evacuating such contents through the spout or funnel 3. As the removable parts 11 and 16 30 are held by their respective pins 13 and 18, they remain in place despite such tilting.

Having described my invention, what I claim as new, and desire to secure by Letters Patent, is:

35 1. In a device of the character described, a hopper having a delivery opening at one end, a removable gate closing said opening, and a U-shaped division contrivance mounted removably and adjustably across said 40 hopper, whereby compartments are provided at either side of said contrivance beside that within it.

2. In a device of the character described,

a hopper having a delivery spout at one end, a removable gate for closing said spout, a division contrivance crossing said hopper removably, means for adjustably securing it thereacross, said contrivance being a U-shaped body with open ends, and means removably and adjustably mounted within 50 said contrivance adapted to variably change its volume for receiving a proportion of an ingredient of the whole compound of hopper contents.

3. In a device of the character described, a hopper mounted tiltingly, said hopper having a delivery spout, a removable closure closing said spout, a division contrivance removably seated across said hopper, said hopper having engaging means along opposite 60 ends graduated in their interspaces, and said contrivance having securing means thereon adapted to coengage with any of said engaging means to detachably secure it in adjusted positions thereacross.

4. In a device of the character described, a tilttable hopper having an outlet at one end, a gate removably seated in the hopper to close said outlet, a U-shaped contrivance with open ends one of which is directed to deliver into 70 said outlet, means for detachably securing said contrivance across said hopper adjustably to provide compartments in the hopper of adjustably varied volumes, another division contrivance removably mounted in the 75 first-mentioned contrivance slopingly to deliver the superincumbent material thereupon to said outlet, and means for releasably securing the second-mentioned contrivance in differently adjusted sloping positions within so the first-mentioned contrivance to adjustably vary the volume of the latter fractionally relatively to the related contents of the other compartments of the hopper.

In testimony whereof I affix my signature.

ROBERT W. MILLER.
